UNITED STATES PATENT OFFICE.

WILL C. BOY, OF BLUFF CITY, TENNESSEE.

VALVE.

1,152,280.

Specification of Letters Patent. Patented Aug. 31, 1915.

Application filed March 18, 1914. Serial No. 825,490.

To all whom it may concern:

Be it known that I, WILL C. BOY, a citizen of the United States, residing at Bluff City, in the county of Sullivan and State 5 of Tennessee, have invented a new and useful Improvement in Valves, of which the following is a specification, reference being had to the accompanying drawing.

My improvement relates particularly to 10 the valve which controls the flow of water into the air chamber of a hydraulic ram.

The object of the improvement is to produce such a valve with accessories which render it highly sensitive and efficient and 15 permit economical manufacture and long wear.

In the accompanying drawings Figure 1 is an upright sectional view of the lower portion of a hydraulic ram air chamber embodying my improvement; Fig. 2 is a view looking down upon the valve stem and accessory parts, a portion of the upper nut on the valve stem being broken away; Fig. 3 is a section on the line, 3—3, of Fig. 1.

Referring to said drawings, 1 is the lower portion of the side wall of the air chamber of a hydraulic ram. At its lower edge, said wall has an outward-directed flange, 2. A horizontal base plate, 3, forms the bottom 20 wall of the chamber and bears against the bottom of the flange, 2, and is secured to said flange by means of bolts, 4. A port, 5, is formed in the base plate, 3, and a pipe, 6, is screw threaded to the base plate to register with the port, 5, for the delivery of water through said port into the air chamber. Above the base plate, 3, is a valve head, 7, extending across the port, 5, and having a stem, 8, extending upward.

Three standards, 9, rise from the base plate equidistant from the axis of the port, 5, and equidistant from each other. The standards are secured to the base plate by bolts, 10. Each standard has two bolts, 11, 30 extending horizontally through the standard transversely to lines which are radial to the valve stem, one of the bolts on each standard being located above the other.

The valve stem, 8, is screw threaded, and 40 near its base it is surrounded by two nuts, 12. Between said nuts the stem is loosely surrounded by a plate, 13, having ears, 14, extending outside of the nuts and being located equidistant from each other or on 45 three lines which radiate from the stem axis at equal angles. On the upper portion of

the stem, 8, are two similar nuts, 15, and between said nuts is a plate, 16, having three ears, 17, similar to the plate, 13 and ears, 14. Three lower contracting coiled springs, 18, 60 have one end joined to the ears, 14, of the plate, 13, while the other end extends to and is secured by one of the lower bolts, 11, the spring having a straightened end, 19, folded upon itself, and lying at opposite sides of the bolt and between the standard and a washer, 20, surrounding the bolt. When the bolt has been loosened, the end, 19, may be moved toward or from the valve stem to vary the tension of the spring. Similar 65 upper springs, 21, have one end secured to the ears, 17, of the plate, 16, while the other end is similarly provided with a folded part, 22, which is folded upon itself and lies at opposite sides of one of the upper bolts, 11, 70 between the standard and a washer, 20, on said bolt. When the bolt has been loosened, the part, 22, may be moved toward or from the nuts, 15, and the bolt again tightened to 75 change the tension of the spring.

The plates, 13 and 16, are so seated on the stem as to bring one of the ears, 14 and 17, into an upright plane cutting the stem axis and one of the standards, 9; and each spring, 18, extends from one of the said ears, 17, to 80 the nearest standard, 9, and each spring, 21, extends from one of the ears, 17, to the nearest standard, 9.

The bolts, 11, to which the upper springs, 21, are attached are located lower than the 85 level of the upper plate, 16, so that said springs are inclined and pull downward as well as outward from the axis of the stem, 8. The bolts, 11, to which the lower springs, 18, are attached are shown a little higher 90 than the level of the plate, 13, when the valve is seated, so that said springs tend somewhat to lift the stem from its seat on the base plate. But this tendency is fully overcome by the stronger downward pull of 95 the more oblique upper springs, 21. The inclination of the lower springs is needed only to avoid interference between the springs and the valve head when the latter is tilted on account of a solid body lodging 100 between said head and the base plate. This is the only reason for slanting said lower springs, and they may be regarded as substantially horizontal and tending only to draw the lower portion of the valve stem 105 sidewise toward its proper position.

The tension of the springs, 18 and 21, may

be varied, individually, in the manner already described; and the tension of the springs, 18, may be varied collectively by raising or lowering the plate, 13, which is done by raising or lowering the nuts, 12. The tension of the springs, 21, may be adjusted collectively by raising or lowering the plate, 16, which is done by raising or lowering the nuts, 15. Either of the two lower 10 nuts may be used as a jam nut to secure the other to prevent turning on account of jarring. The same is to be said of the two upper nuts, 15. The upper springs, 21, are to be so adjusted as to pull downward on the stem, 8, with sufficient force to promptly seat the valve, 7, on the base plate when the pressure in the air chamber approximately equals the pressure below the valve.

The combined action of all the springs 20 tends to hold the valve stem in the upright position and on the axial line of the port, 5; yet the entire engagement of the valve stem is yielding, the valve being free to move upward and both ends being free to move sidewise in response to any force which is sufficient to overcome the pull of the springs in the opposite direction. Within a limited range, the valve stem and valve head are thus mounted to permit universal 25 movement. The purpose of this movement is to permit exact seating of the lower face of the valve head upon the upper face of the base plate, 3, under ordinary circumstances, and to permit the closest approximation to full seating when a foreign object, such as a piece of gravel or wood, lodges between the valve head and the disk, 3. The valve stem then becomes tilted, its upper end leaning in the direction opposite 30 the obstruction, and the portion of the valve head opposite the foreign body resting on the seat. To permit such leaning of the valve stem, there must be a lateral adaptation or adjustment of the entire stem, such adjustment increasing from the lower end upward. If this lateral adaptation were not 35 permitted and the valve stem were limited to direct up and down movement, a foreign body lodging between the base plate and the valve head would hold the entire head as far from the base plate as said foreign body is high, leaving about twice as much opening as is the case when one side of the valve head rests on the foreign body and the other 40 rests on the base plate. In such apparatus it is important to reduce the downward flow of water to the minimum when such a for-

55 eign body interferes. Usually such body is released when the next pulsation or stroke lifts the valve.

The upper springs and the lower springs 60 constitute universally yielding means engaging the valve stem at two elevations and tending to position the valve stem relative to the seat. It may also be said that the lower 65 springs constitute universally yielding means applied to the lower portion of the valve stem drawing substantially horizontally and tending to position the lower portion of the valve stem relative to the seat, while the upper 70 springs constitute means tending to retain the upper portion of the valve stem in normal position, but allow lateral movement within a limited range.

I claim as my invention,

75 1. In an apparatus of the nature described, a base having a port, a valve for closing said port, a stem rising from said valve, and universally yielding means engaging the valve stem at two elevations and tending to position the stem relative to the seat, substantially as described.

2. In an apparatus of the nature described, a base plate having a port, a valve for closing said port, a stem rising from said valve, universally yielding means applied to the lower portion of the valve stem and acting substantially horizontally to position the lower portion of the valve stem relative to the port, and means tending to 85 retain the upper portion of the valve stem in normal position but allowing lateral movement within a limited range, substantially as described.

90 3. In an apparatus of the nature described, a base plate having a port, a valve head adapted to seat upon said plate above said port, a stem rising from said head, contracting springs applied to the lower portion 95 of the valve stem and acting substantially horizontally to position the lower portion of the valve stem relative to the seat, and contracting springs tending to retain the upper portion of the valve stem in normal position 100 but allowing lateral movement within a limited range, substantially as described.

105 In testimony whereof I have signed my name, in presence of two witnesses, this 2nd day of March, in the year one thousand nine hundred and fourteen.

WILL C. BOY.
